UNITED STATES PATENT OFFICE.

WALTER S. ADAMS, OF PHILADELPHIA, PENNSYLVANIA, ASSIGNOR TO
JOHN A. BRILL, OF SAME PLACE.

CAR-TRUCK.

SPECIFICATION forming part of Letters Patent No. 665,359, dated January 1, 1901.

Application filed July 21, 1898. Serial No. 686,499. (No model.)

To all whom it may concern:

Be it known that I, WALTER S. ADAMS, a citizen of the United States, residing in the city and county of Philadelphia, State of Pennsylvania, have invented certain new and useful Improvements in Car-Trucks, of which the following is a specification.

My invention relates to car-trucks generally, and more particularly to the class of electrically-propelled car-trucks known as "maximum traction," or those which generally have large driving-wheels that carry the main weight of the motor and the superposed car-body and smaller trailing or guiding wheels. In this class of trucks, owing, among other things, to the pivotal point being eccentric to the truck-center and adjacent the driving-wheels, there is danger that the small wheels will jump the track, particularly when the small wheel is traveling ahead of the large driving-wheels; and the main object of my invention is to provide means for keeping the small wheels down upon the track, and particularly so while the truck is passing around curves. In carrying out this portion of my invention in its preferred form I provide a car-truck having large and small wheels and a car-body which may have a bolster or beam extending transversely thereof and having at its under side a recess that inclines from a central point outwardly in opposite directions, and in this recess a spring-acting rod or plunger fits and connects with the car-truck at a point preferably between the two pairs of wheels and at the longitudinal center of the truck, forming an end bearing, whereby as the end of the truck tends to rise the rod or plunger and the spring will act to resist such tendency. By having the inclined recess the arrangement is such that when the car is turning a curve the spring-acting rod or plunger will act with increased force upon that part of the truck to hold it down firmly, and this feature is important, because the tendency of the wheels to jump from the rails is greater while the truck is rounding a curve than at other times.

The invention also consists in the novel details of improvement and the combinations of parts, that will be more fully hereinafter set forth and then pointed out in the claims.

Reference is to be had to the accompanying drawings, forming part hereof, wherein—

Figure 1 is a partly-broken side elevation of a car-truck embodying my invention. Fig. 2 is a plan view thereof. Fig. 3 is a cross-section on the plane of the line 3 3 in Fig. 1. Fig. 4 is a vertical section on the plane of the line 4 4 in Fig. 3. Fig. 5 is a sectional detail about on the same plane as Fig. 4. Fig. 6 is a sectional elevation on line x x, Fig. 1; and Fig. 7 is a perspective of the body-end rub-plate.

Similar numerals of reference indicate corresponding parts in the several views.

In the accompanying drawings, 1 indicates the main driving-wheels, and 2 the smaller trailing wheels, arranged in a manner similar to the usual practice in the maximum-traction trucks. At 3 are the axle-boxes for the axles 4, which are guided in yokes 5 6 of the truck-frame, 7 being side bars that connect the yokes, and at 8 are springs interposed between the axle-boxes 3 and the tops of the yokes 5 6. At 9 is a cross-bar at the outer or forward end of the truck, which connects with the arms 10, that project from the axle-box yokes 5, and at 11 is a cross-bar connecting the side bars 7 at a point between the wheels 1 2. (See Fig. 2.) The cross-bar 11 is shown as turned on edge and having its outer ends 11^a bent parallel to the side bars 7 and placed against the same and secured thereto by bolts 12. The parts above described may, however, be of any usual or suitable construction.

The yokes 5 6 are open at the bottom to permit the axle-boxes 3 to be inserted, and at the lower ends of the yokes is a retaining-bar 13, having upturned ends 13^a, being substantially in U form, and these upturned ends 13^a are secured to the vertical bars of the yokes, for which purpose the lower ends of the yokes on the outer sides have depressions to receive the ends of retainer 13, which may be secured in position by bolts or screws or otherwise. This retainer 13 braces the lower ends of the yokes and keeps the axle-boxes properly within the yoke, at the same time affording a simple and cheap construction and one which enables the parts to be readily adjusted.

At 14 is a car-body, which is shown resili-

- ently supported upon the truck by means of spring-supported side bearings and confined in pivotal relationship to the truck in the manner recited. 15 is a restraining-plate secured 5 to the sill 16 of the car and having a depending segmental web 15^a on the outer side, and 17 is a yoke carrying a rotatable friction-roller 17^a, adapted to bear against the plate 15^a. Between the plate 15 and the yoke are friction-10 plates 15^b 15^c, secured, respectively, to the yoke and plate. From the yoke depend posts 18, that pass through apertures in an arm 19, projecting from the yoke 5, parallel with and directly over the side bar 7, the rods 18 having 15 shoulders 18^a, that rest on plates 20, that are supported upon springs 21, which surround said posts, said springs resting in plates 22 on the side bars 7, and said side bars have apertures 23, through which the posts 18 pass, 20 pins 24 on said posts serving to prevent displacement of the posts. The means for resiliently supporting the car-body upon the truck and those employed to secure a pivotal support of the car may be altered, if desired. 25 As the car-body is supported upon said bearings I, provide a draw-bar for connecting the truck with the car-body for the purposes of drawing the car.
- At 25 is a draw-bar, shown in the form of a 30 post, depending from the car-body and which may be secured thereto at its upper end in any suitable manner, but by preference as shown herein. The draw-bar 25 passes through an aperture in a plate 26, that is secured to the platform-knee 27, so that the greatest strain is transmitted from said draw-bar directly to the platform-knee through the plate 26. This plate also braces the draw-bar in every direction, so that when the car is rounding curves or proceeding straight ahead the strain on the draw-bar will be evenly transmitted to the platform-knee.
- The connection I have shown of the draw-bar with the car-truck is as follows: At 28 is 35 a casting secured to the cross-bar 9 and having a groove in the arc of a circle described around the pivotal center of the truck and provided in the bottom with a slot 29, through which recess the draw-bar 25 passes. (See Fig. 1.) Within the recess 28^a of casting 28 is placed a sliding block 30, (see Fig. 2,) having an aperture through which the draw-bar 25 passes, and on the top of the casting 28 is placed a plate 31, having a groove 40 corresponding to the groove 29, which plate may be held in position by bolts 32, whereby the block 30 is confined within the recess of casting 28 and is adapted to travel there-through, the side or bearing faces of said 45 block being curved to correspond to the curves of the bearing-walls of the casting 28. Thus the draft is transmitted from the draw-bar 25 to the block 30 and casting 28 and thence to the bar 9 and the truck-frame. It is evident, however, that as to other features of 50 my invention any other suitable means than that shown may be provided for connecting the draw-bar with the truck for the purposes of draft and that other draft devices may be employed.
- The means to assist in holding the small wheels 2 down upon the track (in other words, the spring-compressor) are as follows: 35 is a body-bolster extending across the bottom of the car-body and in the form of a channel-beam, with its webs extending downwardly, and in this hollow or channel-like bolster is located a beam or bar 36, which may be secured therein in any suitable manner, and at the central line of the car-body the beam 36 55 has a recess or depression 37, that inclines outwardly and downwardly in opposite directions from a central point 38, somewhat in V form, as shown in Fig. 3, and from the points 39 where the recess 37 ends the under 60 surface of the beam is preferably inclined upwardly and outwardly toward its ends at 40. At 41 is a wear or rub plate that fits the bottom of the beam 36 and has a central bent portion 42, that corresponds to the depression or recess 37 in the beam 36, the plate 41 acting as a friction or wear plate. On the truck is a rod or plunger 43, shown provided with a head 44, the upper surface of which head is inclined from a central point 65 outwardly in opposite directions at 45 to correspond to the inclines 42 of the recess 37 in beam 36. (See Fig. 3.) The head 44 is shown guided in an aperture 46^a in a yoke or casting 46, that is secured to and extends upwardly from the cross-bar 11, and said rod at its lower end is guided in an aperture 46^b in the base of the yoke or casting 46. The rod or plunger 43 is shown provided with a reduced portion just below the head 44, which 70 is screw-threaded at 47 to receive the threaded aperture in a cap-piece or plate 48, that rests upon a spring 49, which is coiled around the rod or plunger 43 and rests at its lower end in a pocket or seat 50 at the bottom of 75 the yoke or casting 46, fitting around the apertured lug 50^a. The yoke or casting 46 is shown as provided with a plate or web 51, that rests against one side of the cross-bar 11, and may be bolted thereto, and with lips 52, 80 that rest upon the upper edge of the cross-bar 11. (See Figs. 4 and 5.) Near the outer ends of the plate 51 of the yoke 46 are overhanging lips 53, that form recesses to receive the upper edge of the cross-bar 11, whereby 85 the same is held in proper position upon the cross-bar and kept from tilting thereon. At 54 are webs near the ends of the casting, that extend outwardly and serve to strengthen the structure at the base-plate 51. The arrangement is such that when the parts are in their proper positions the head 44 of the rod or plunger 43 will be held against the wear-plate 41 of the beam 36, compressing the springs 49 to the required amount, and if the 90 small wheels 2 tend to rise from the track the spring-acting plunger by finding an abutment at the car-body will tend to hold the wheels down upon the track. When the car

passes around a curve and the trucks swing or move laterally beneath the car-body, or vice versa, and especially when the small wheels are running ahead of the large wheels, the position of the spring-acting plunger relatively to the central line of the car will change, during which time the head 44 will pass under the incline of the recess 37 in the beam 36, thereby putting the spring 49 under more or less tension, and the greater the tension thus produced on the spring by the downward movement of the rod or plunger 43 the greater will be the tendency to hold the small wheels 2 down upon the track.

15 I do not limit my invention to the precise details of construction shown and described, as they may be varied without departing from the spirit thereof.

Having now described my invention, what

20 I claim is—

1. The combination of a car-truck, and a car-body pivotally mounted thereon; a bolster or beam on the car having a recess on its under surface that inclines from a central point outwardly in opposite directions, and with a spring-acting rod or plunger connected with the car-truck and having a double-beveled solid head fitting in said recess, substantially as described.

25 2. The combination of a car-truck, with a car-body pivotally mounted thereon; a bolster or beam extending transversely thereof and provided on its under surface with a recess that inclines from a central point outwardly in opposite directions, a yoke secured to a cross-bar of the truck, a plunger guided by said yoke and having a double-beveled solid head resting in said recess, and a spring acting on said plunger to keep the head of 30 the same within said recess, substantially as described.

35 3. The combination of a car-truck, with a car-body having a bolster extending transversely thereof and provided on its under surface with a recess that inclines from a central point outwardly in opposite directions, a yoke or casting secured to a cross-bar of the truck, said yoke having an aperture at its upper end and a pocket at its lower end, a 40 plunger having a head guided in said aperture and also guided in an aperture at the lower end of said yoke or casting, a spring located in said pocket, and a cap or plate connected with said plunger and acting upon 45 said spring, substantially as described.

50 4. The combination of a car-truck, with a car-body having a bolster extending transversely thereof and provided on its under surface with a recess that inclines from a central point outwardly in opposite directions, and with a yoke or casting having upper or lower alined apertures and a pocket at the lower part forming a post, a plunger having a head guided in the upper aperture and its 55 end portion guided in the lower aperture, a spring surrounding said plunger and said post and resting in said pocket, and a cap or plate

adjustably carried by said plunger and resting on said spring, substantially as described.

5. The combination of a car-truck having 70 large and small wheels, with a car-body pivotally mounted thereon, said car having a bolster extending transversely thereof and provided on its under surface with a recess that inclines from a central point outwardly 75 in opposite directions, and with a spring-acting rod or plunger connected with the car-truck and having a solid head, the upper surface of which is inclined outwardly in opposite directions from a central point to correspond with the inclines of said recess and guides for said plunger mounted upon the truck, substantially as described.

6. The combination of a car-truck, with a car-body having a bolster or beam extending 85 transversely thereof and provided on its under surface with a recess that inclines from a central point outwardly in opposite directions, a plate having a bent portion to correspond with and fit within said recess, and a 90 spring-acting plunger connected with the truck and having its head normally resting against said plate, substantially as described.

7. The combination of a car-truck, with a car-body having a bolster provided with a 95 channel opening downward, a beam located in said channel and provided on its under surface with a recess that inclines from a central point outwardly in opposite directions, a 100 wear-plate having a depression that corresponds with and fits within said recess, and with a spring-acting plunger connected with the car-truck and having its end located in said recess and bearing against said wear-plate, substantially as described.

105 8. The combination of a car-truck, with a car-body having a bolster extending transversely thereof and provided on its under surface with a recess that inclines from a central point outwardly in opposite directions, 110 and with a yoke or casting having alined apertures, said yoke or casting having a plate to rest against a cross-bar of the truck-frame and overhanging lips to rest upon said cross-bar, a plunger fitting in the apertures of said 115 yoke or casting and having a solid head bearing against said bolster or beam, and a spring interposed between the plunger and the yoke or casting to resist the downward movement of the car-body, substantially as described.

120 9. The car-body having a cross-bolster, having a plate secured in a correspondingly formed recess in the bolster, said plate having the outwardly-extending flat horizontal sections 41 affording uninterrupted bearing- 125 surfaces 41 and intermediate and upwardly-converging portions 42, substantially as described.

130 10. A car-truck, provided with a bearing-support comprising a yoke having the seat 50, the guide 46^a on the yoke, a block 44 movable in the guide, a spring on said seat, a cap on the spring connected with said block combined with a car pivoted to the truck and hav-

ing a bearing engaging said block, substantially as described.

11. A car-truck, provided with a bearing-support comprising a yoke having the seat 50, upwardly-extending apertured lug 50^a, and guide 46^a, a block movable in the guide, a spring on the seat around the lug, a rod extending from the block to and into the aperture in the lug, a cap on the spring secured 10 to said rod, combined with the car pivoted to the truck and having a bearing engaging said block, substantially as described.

12. The combination in a car-truck having a cross-bar of the yoke 46 secured to the cross-bar, said yoke having the guide 46^a, of the block 44 movable in the guide, said block having a top comprising two upwardly-converging bearing-surfaces, and a spring on 15 said yoke to resist downward movement of 20 the block, substantially as described.

13. The combination with the yoke having the seat 50, the guide 46^a on the yoke, a block 44 movable in the guide, a spring on the seat and a cap on the spring detachably connected to the block, substantially as described. 25

14. The combination with the yoke having the seat 50, the guide 46^a on the yoke, a block 44 movable in the guide, a rod extending from the block and guided in the said seat, a screw-thread on the rod, a spring on the 30 seat and a cap having a threaded aperture engaging the rod and resting on the spring, substantially as described.

Signed in the city and county of Philadelphia, State of Pennsylvania, this 1st day of 35 July, 1898.

WALTER S. ADAMS.
